GUN-FIRING MECHANISM

Bryan P. Joyce, East Orange, N. J., assignor to
American Armament Corporation, New York,
N. Y., a corporation of Delaware

Application October 17, 1940, Serial No. 361,621

2 Claims. (Cl. 29—27)

The invention aims to provide a simple and effective firing mechanism designed primarily for anti-tank guns and the like.

In carrying out the above end, a further object is the provision of a novel arrangement of parts for transmitting movement from a firing button or the like to a firing trigger of the gun.

Yet another aim is to make novel provision whereby the firing button may be held in safety position.

With the foregoing in view, the invention resides in the novel subject matter hereinafter described and claimed, description being accomplished by reference to the accompanying drawings.

Figure 1 is a side elevation showing an anti-tank gun equipped with the invention.

Figure 2 is an enlarged fragmentary top plan view.

Figure 3 is a fragmentary side elevation partly in section as indicated by the arrow 3 of Fig. 2.

Figure 4 is a vertical transverse sectional view as indicated by the lines 4—4 of Figs. 2 and 3.

Figure 5 is a vertical longitudinal section partly in elevation as indicated by line 5—5 of Fig. 2.

Figure 6 is a vertical transverse section substantially on line 6—6 of Fig. 2.

Figure 7 is a disassembled perspective view showing the trigger-operating roller and the rock shaft and arms with which it is associated.

Figure 8 is an enlarged horizontal sectional view through the firing button and associated parts as indicated by line 8—8 of Fig. 5.

Figure 9 is a vertical transverse sectional view on the plane indicated by line 9—9 of Fig. 8.

Figure 10 is a rear elevation of the firing button and associated parts as indicated by the arrow 10 of Fig. 5.

Preferred features of construction have been illustrated and will be rather specifically described, with the understanding, however, that within the scope of the invention as claimed, variations may be made.

An anti-tank gun is shown in which the gun proper 12 is mounted on a cradle 13, said cradle having trunnions 14 pivotally mounted in bearings 15 on a top carriage 16, said top carriage being pivoted at 17 on a vertical axis to an appropriate bottom carriage 18. The cradle 13 is provided with segments 19 instrumental in elevating and depressing the gun, and the bottom carriage 18 is provided with a curved rack 20 which is instrumental in traversing the gun.

Rigidly secured to one side of the top carriage 16 by cap screws or the like 21, is a casing 22

containing gearing necessary in effecting elevation and traversing. A vertical shaft 23 extends through this casing and is provided on its lower end with a pinion 24 meshing with the rack 20. Within the casing 22, the shaft 23 is equipped with a worm gear 25 meshing with a worm 26 on a horizontal shaft 27 which extends into said casing, the rear end of this shaft 27 having an appropriate hand wheel 28. By rotating this hand wheel, it will be seen that the top carriage 16 will be turned upon its pivot 17 to traverse the gun as required.

A horizontal shaft 29 extends from the interior to the exterior of the casing 22 and carries pinions 30 meshing with the segments 19, said shaft having a worm gear 31 within said casing meshing with a worm 32 on an inclined shaft 33 which extends across the casing 22 and projects rearwardly from the latter, the rear end of said shaft 33 being equipped with a hand wheel 34. Turning of this hand wheel causes turning of the shaft 29 to elevate or depress the gun as required. This hand wheel 34 is by preference in the form of a knob of such size that it may be readily gripped by one hand, and the firing button 35 for the gun is so associated with the rear of said hand wheel 34 that said button may be pushed with the palm of the same hand which operates said hand wheel, it thus being unusually convenient to fire the gun the instant it is elevated or depressed to the required extent.

The firing trigger of the gun is indicated at 36, (see more particularly Figs. 2, 3 and 4) and in the present showing, it is necessary to depress said trigger from engagement with a lug 37 on a longitudinal rod 38, to cause firing of the gun. The rod and trigger are mounted on the gun cradle 13, and near said trigger this cradle is provided with a bracket 39 having a bearing 40 disposed transversely of the gun. Within this bearing, a short rock shaft 41 is mounted (see Figs. 2 and 7). One end of this rock shaft has a crank arm 42 carrying a roller 43 which overlies the trigger 36, and a second crank arm 44 is provided on the other end of said rock shaft 41 for a purpose to appear.

A member 45 is pivotally mounted on an axis which is permanently aligned with the trunnions 14, said member having one upwardly projecting arm 46 and one downwardly projecting arm 47. The arm 46 is connected by a link 48 with the arm 44 of the rock shaft 41 above described, so that rocking of the member 45 in the proper direction will cause depression of the roller 43 on the other arm 42 of said rock shaft 41, thus ef-

fecting release of the trigger 36 and causing firing of the gun.

A swivel connection 49 is slidably mounted on the above described shaft 33 immediately in front of the hand wheel 34, said swivel connection being shown in elevation in a number of the views and in horizontal section in Fig. 8. From this latter view, it will be seen that the connection 49 includes an inner member or collar 59 and an outer member or collar 51 rotatably connected with each other. The outer collar 51 is connected by a link 52 with the downwardly projecting arm 47 of the pivoted member 45. Due to construction later described, the inner collar 59 is operatively connected with the push button 35. Thus, pushing of this button causes the swivel connection 49 and the link 52 to turn the pivoted member 45 in gun-firing direction, whereupon said member operates the link 48 and the latter actuates the bell crank (44, 41, 42, 43) to trip the firing trigger 36, causing firing of the gun.

The member 45 above described is preferably in the form of a short length of tubing, and to rotatably mount said member on an axis permanently aligned with the axis of the trunnions 14, I prefer to employ a headed stud 53 threaded at 54 into one of said trunnions.

For the construction now to be described, directly associated with the firing button 35, the hand wheel 34, and the swivel connection 49, reference is made more particularly to Figs. 8 and 9. From these views, it will be seen that the rear portion of the hand wheel 34 is formed with a central recess 55 of circular outline. The firing button 35 is slidable in this recess, and pins 56 parallel with the shaft 33, operatively connect said firing button with the inner collar 59 of the swivel connection 49, said pins being preferably in the form of screws, as shown. These pins pass slidably through openings 57 in the hand wheel 34 and there are preferably three of said pins to effectively guide the movements of the push button 35. A suitable compression spring 58 normally holds this push button in its rearmost position but whenever said push button is forced forwardly, it forwardly moves the swivel connection 49 to effect gun-firing. During rotation of the hand wheel 34 to elevate or depress the gun, the inner member 59 of said swivel connection simply rotates idly in the outer member 51 of said connection.

The push button or firing button 35 preferably consists of inner and outer members 59 and 60 rotatably connected with each other, said inner member 59 being secured to the pins 56. The member 59 is in the form of a shell rotatable upon the inner member 59 on an axis aligned with the axis of the shaft 33. This shell 60 carries one or more forwardly projecting pins or the like 61 which will abut the inner wall of the recess 55 (in wheel 34) and prevent operation of the push button 35 unless said shell 60 be turned to a predetermined position. When the shell is turned to this position, the pins or the like 61 align with recesses 62 in the hand wheel 34 and, therefore, said pins or the like will not interfere with forward movement of the button 35 to fire the gun.

The inner member 59 of the firing button 35 preferably carries the words "Fire" and "Safe," as seen in Fig. 10, and shell 60 has an opening

63 through which said words are visible one at a time. When "Fire" is visible the pins or the like 61 are aligned with the recesses 62 and there is nothing to prevent forward movement of the firing button 35 to fire the gun. When the shell 60 is turned, however, to display the word "Safe" in the window 63, the pins or the like 61 are out of alignment with the recesses and firing movement of the button 35 is, therefore, prohibited.

From the foregoing, taken in connection with the accompanying drawings, it will be seen that novel and advantageous provision has been made for carrying out the objects of the invention, and while preferred details have been illustrated, attention is again invited to the possibility of making variations within the scope of the invention as claimed.

Attention is not only invited to the novel structure and relation of elements shown more particularly in Fig. 8, but to the simple and advantageous operating connections between the swivel connection 49 and the trigger-releasing member 43. I am, of course, aware that these operating connections will receive some movement when the gun is either elevated or depressed, but in an anti-tank or similar gun, the extent of depression is usually about five degrees and the extent of elevation about fifteen degrees. Thus, any movement imparted to the roller 43 with respect to the trigger 36 during elevation or depression of the gun will be negligible and will to a large extent be compensated for by lost-motion in the connections between said roller and the swivel connection 49.

I claim:

1. In a gun including firing means and barrel-directing means, said barrel-directing means having a hand wheel by means of which it may be operated; a push button carried by said hand wheel and mounted for pushing movement with respect to said hand wheel and for turning movement with respect to said hand wheel, means operatively connecting said push button with said firing means for actuating the latter when said push button is pushed, and safety means interposed between said push button and said hand wheel and controlled by turning movement of said push button with respect to said hand wheel for locking said push button when this button is turned to one position and for releasing said push button when this button is turned to another position.

2. In a gun including firing means and barrel-directing means, said barrel-directing means having a hand wheel by means of which it may be operated; a push button carried by said hand wheel and mounted for pushing movement with respect to said hand wheel and for turning movement with respect to said hand wheel, means operatively connecting said push button with said firing means for actuating the latter when said push button is pushed, safety means interposed between said push button and said hand wheel and controlled by turning movement of said push button with respect to said hand wheel, for locking said push button when this button is turned to one position and for releasing said push button when this button is turned to another position, and coating indicating means on said hand wheel and push button for indicating said positions of said push button.

BRYAN P. JOYCE.
